UNITED STATES PATENT OFFICE.

IRVING STANLEY, OF NEW YORK, N. Y., ASSIGNOR TO ANGEL INTERNATIONAL CORPORATION, OF NEW YORK, N. Y., A CORPORATION OF MAINE.

APPARATUS FOR MAKING RECEPTACLES OR CONTAINERS.

Application filed April 25, 1921. Serial No. 464,347.

To all whom it may concern:

Be it known that I, IRVING STANLEY, a citizen of the United States, and a resident of the borough of Manhattan, in the city, county, and State of New York, have invented certain new and useful Apparatus for Making Receptacles or Containers, of which the following is a specification.

This invention relates to apparatus for making receptacles or containers by wrapping a sheet of material, such as paper, around a mandrel with the longitudinal edges in overlapped relation and then applying a sealing strip to the overlapped edges to form a tube preferably of truncated conical shape, and to combine with said apparatus means to which a tube is delivered from the mandrel to form and apply a closure to said tube to produce a receptacle or container, and it is the primary object of the invention to provide improved apparatus for this purpose which is simple and cheap in construction for the work which it is to perform and efficient in operation.

It is another object of the invention to provide improved means in apparatus of this character to feed a sheet to and wrap it around a mandrel to tubular form, and provide improved means for sealing and securing the sheet upon the mandrel into tubular form.

It is another object of the invention to provide improved means to receive a tube ejected from the tube forming means and releasably hold the same, and while held thereby successively positioning the holder to present a tube carried thereby to means to form and apply a closure to said tube, to means to secure the closure in the tube, and to position to release the tube from the holder.

It is a further object of the invention to provide in apparatus of this character improved means for forming a closure preparatory to applying the same to the tube by stamping a disk from an intermittently fed web and peripherally flanging the disk,

and simultaneously with the flanging of the disk applying the same to the tube.

Other objects and advantages will herein-after appear.

In the drawings accompanying and forming a part of this specification Figure 1 is a plan view illustrating an embodiment of apparatus for carrying out the invention.

Figure 2 is a side elevation looking in the bottom of Figure 1 and partly broken away.

Figure 3 is an end elevation looking at the left of Figure 1.

Figure 4 is a cross sectional view taken substantially on the line 4—4 of Figure 1 looking in the direction of the arrow.

Figure 5 is a cross sectional view taken substantially on the line 5—5 of Figure 1 looking in the direction of the arrow and showing in dotted lines transferring means in relation to the apparatus to transfer a formed receptacle to paraffining apparatus.

Figure 6 is an end elevation, partly in section, looking at the right of Figure 1.

Figure 7 is a perspective view of the receptacle or container produced by the apparatus.

Figure 8 is an enlarged sectional detail view of means to stamp a disk from a web and peripherally flange the same and showing the manner of applying the flanged disk as a closure to one end of the tube.

Figure 9 is an enlarged sectional detail view of means for upsetting the material of the disk flange and the tube to secure the disk in the tube.

Figure 10 is a cross sectional view of a portion of the container or receptacle to show the relation of the sealing and securing means to the longitudinal overlapped edges of the tube.

Figure 11 is a front elevation to show the arrangement of a series of upsetting heads for the material of the disk flange and tube.

Figure 12 is an enlarged longitudinal sectional view to show the mounting of the actuating means for the upsetting heads.

Figure 13 is a detail view in end elevation looking at the left of Figure 4 of the means to wrap a sheet around a mandrel, and showing said means in normal relation to the mandrel with a sheet interposed below the mandrel and between the mandrel and sheet wrapping means.

Figure 14 is a side elevation of the means to wrap a sheet around a mandrel and showing the same in normal position relative to the mandrel with a sheet interposed between said means and the mandrel preparatory to be wrapped around the mandrel.

Figure 15 is a detail view in end elevation of the means to wrap a sheet around the mandrel and showing said means in relation to the mandrel when the sheet has been wrapped around the same.

Figure 16 is a detail view in plan and partly in section of the means to wrap a sheet around the mandrel; and

Figure 17 is a detail view of means to moisten a gummed surface of a web preparatory to applying the same to the overlapped edges of the sheet wrapped around the mandrel to seal and secure said edges together.

Similar characters of reference designate like parts throughout the different views of the drawings.

In the embodiment of the invention shown in the drawings the operative mechanism of the apparatus is mounted upon a supporting standard or base B, and said mechanism is actuated from a cam driving shaft S journalled in bearings mounted upon the base and driven from a suitable source of power, shown as an electric motor M operatively connected to the shaft by a worm on the motor shaft meshing with a worm wheel 18 loose on the drive shaft and operatively connected and disconnected from the shaft by a clutch one member of which clutch is carried by the worm wheel and the other clutch member 19 slidably mounted upon the shaft and rotatable therein, and adapted to be thrown into and out of clutching position by a lever 20 having a bifurcated end carrying pins to engage an annular groove in the clutch member 19, as shown at 21, the lever being operable by a rod 22 pivotally connected at one end to one end of the lever and slidably supported in bearings upon the base.

A table 23 is adjustably supported by the base to support a pile or sheets or blanks 24 cut to proper shape to form a tube, in the present instance a tube of truncated cone shape, the blanks being maintained in position upon the table by posts 25. The sheets are fed from the pile and positioned upon a support consisting of a pair of flat members 26 fixed upon the base in parallel spaced relation and adapted to support a sheet 27 (Figure 13) upon the upper edges

of said members with the leading edge engaging with gauge lugs 28 on said members, said members being located and supporting a sheet below a mandrel 29 around which the sheet 27 on the support is wrapped, said mandrel being of truncated cone form and fixed at the base to extend in horizontal position from a standard 30 mounted upon the base B.

The sheets are separated and fed from the pile 24 by suction means, consisting of a pair of suction cups carried by tubular connected members 31 the opposite ends of which are closed and the members slidably supported between rollers 32 mounted upon a carriage 33 pivotally supported for oscillatory movement at 34 by brackets 35 mounted upon the base (Figure 5). The tubular suction cup carrying members are connected by a flexible tube 36 to a vacuum pump 37 of the reciprocating piston type the piston of which pump is operatively connected through a rod 38 and actuated by a cam 39 upon the drive shaft. The suction cup carrier is reciprocated by a lever 40 one end of which has a link connection 41 with the carrier. The lever is actuated by a cam 42 on the drive shaft and operatively connected thereto by a rod 43 connected to the other arm of the lever 40. To oscillate the carrier 33 upon the pivot support 34 to move the suction cups into contact with a sheet upon the pile to separate and feed a sheet and to move them out of contact with the sheet when it has been delivered to the sheet support 26, a pair of connected levers 44 pivotally supported upon the bracket 35 have a link connection 45 at one end with the carrier 33, said levers being connected to and rocked by a cam 46 fixed on the drive shaft by an arm 47. To permit of the reciprocatory movement of the suction cup carrier and to provide a compact structure the mandrel 29 is transversely recessed, as shown at 29', Figures 2, 5, 13, 14 and 15 for the passage of the suction cup carrying members.

The table 23 is supported to have adjustment in a vertical direction, and for this purpose is carried by a threaded stem 48 mounted in a half nut 49 carried by a lever 50 pivotally supported at 51 (Figure 1) below the base B, the lever being normally positioned by a spring 52 to engage a stop 53 with the nut engaging the threads of the stem 48. To adjust the table manually, as to lower the table when supplying the pile of sheets thereto, the lever 50 is moved to position to engage a stop 55 thereby moving the nut 49 away from the threaded stem 48 and permitting the table to be lowered or raised. The table is intermittently elevated as the sheets are fed therefrom by ratchet mechanism comprising a ratchet wheel 56 having a splined connection with the sup-

porting stem of the table to rotate the table with the rotation of the ratchet wheel and permit of axial sliding movement of the table. The ratchet wheel is rotated step by step in proper timed sequence with the feeding of the sheets from the pile by a ratchet pawl 57 pivotally carried by a lever 58 hung at one end upon the table stem 48, said lever having a link connection 59 with one end of a rocker arm 60 operatively connected to and actuated by a cam 61 on the drive shaft 30 having a rod 62 connected to the rocker arm 60.

In the operation of wrapping a sheet upon the support 26 around the mandrel the sheet is first clamped substantially midway between its longitudinal edges to the mandrel by means of a vertical reciprocable plunger 63 slidably mounted in a slide or plunger 63' slidably mounted in slideways 64 fixed below the base and pivotally connected to one end of a lever 65 (Figure 5) and actuated by a peripheral cam portion 66 on a cam 67 on the drive shaft through a cam engaging roller carried by a rod 68 connected to the lever 65. After the sheet is clamped to the mandrel as set forth the free ends of the sheet at opposite sides of the sheet clamp 63 are wrapped around the mandrel by a series of oppositely curved fingers 69 fixed to parallel shafts 70 extending parallel with the axis of the mandrel, said shafts being rotatably supported at opposite ends in the slide or plunger 63'. Each of the fingers is arranged with an ear 71 and the ears of opposite fingers are connected by springs 72 to normally yieldingly urge the fingers to position to engage stops on the shafts and assume the position shown in Figure 13 below the mandrel. To wrap the sheet around the mandrel the finger carrying slide or plunger 63' is moved upward causing the fingers 69 to engage the sheet 27 on the support 26 at opposite sides of the clamp 63 moving the sheet upward with the fingers, the fingers as they come in contact with the mandrel being moved laterally and the springs 72 yieldingly though firmly maintain the fingers in contact with the sheet on the mandrel thereby wrapping the sheet around the mandrel under tension. This movement of the finger plunger continues until the fingers engage the top of the mandrel as shown in Figure 15 with the longitudinal edges of the sheet in overlapped relation as shown in Figure 10. The finger carrying slide is actuated by a rocker arm 73 having a bifurcation at one end for the engagement of a transverse pin carried by the slide 63', as shown at 74, (Figures 5, 13 and 14), the other arm of the lever being connected by a rod 75 to the cam 67 to be actuated by the latter.

The overlapped edges of the receptacle or container are sealed and secured together by a gummed strip, such as paper. This strip is applied to the overlapped edges of the sheet after the sheet has been wrapped upon the mandrel with the sheet wrapping fingers in the position shown in Figure 15. This strip is fed from a rolled web 76 (Figure 2) rotatably carried by the standard 30, the web being passed around a guide roller 77 to a pair of superposed feeding rollers, as shown at 78, the lower roller being intermittently and positively actuated by pawl and ratchet mechanism consisting of a ratchet wheel 79 (Figure 1) fixed to a shaft 80 journaled in brackets extending laterally from the standard 30, and a ratchet pawl 81 to cooperate with said ratchet wheel pivotally carried by a pawl 82 actuating arm 83 connected to and operated by a cam 83 on the drive shaft. The shaft is operatively connected to the driven roll of the feeding rollers by a bevelled pinion 84 on the shaft 80 meshing with a bevelled pinion 85 connected to said roller. The web is delivered from the feeding rollers 78 to lie contiguous to the face of a ram or plunger 86 slidably carried by the standard 30 and in juxtaposed relation to the overlapped edges of the sheet upon the mandrel, and the web is guided to the ram by fingers 87 pivotally carried on opposite side of the ram said fingers having a flanged end to engage partially over the face of the ram, as shown in Figures 5 and 17. As the web is delivered by the feed rollers between the face of the ram and fingers 87 the gummed surface of the web is moistened by passing the same over moistening rollers 88 rotatably carried in a liquid carrying trough 89, said trough being positioned and the rollers arranged that a portion of the rollers will project from the trough and engage the web between the flanged portion of the fingers 87. The web as it is fed to the ram passes between a pair of shear blades 90, 91 located between the rear of the ram and the feed rollers, which blades are movable toward each other to sever the fed strip from the web. The blades are provided with segmental toothed portions 92 and both blades are operated by imparting movement to one of the blades. The shears are actuated by a cam or eccentric 93 on the driving shaft operatively connected to the shears by a rod 94 connected to the eccentric 93 and an arm 95 fixed to a rock shaft 96, and an arm 97 on said shaft connected by a link 98 to the extended end of the shear blade 91.

The moistened gummed strip carried by the fingers 87 contiguous to the face of the ram is applied to the overlapped edges of the sheet upon the mandrel under pressure and heat. For this purpose the ram is forcibly moved into engagement with the mandrel by a shaft 99 journaled in the standard 30 having a crank arm 100 connection with the ram the shaft 99 being rocked by a cam or eccentric 101 on the drive shaft opera-

tively connected by a rod 102 to one arm of a bell crank lever 103 (Figure 5), the arm of which lever has a link connection 104 with the shaft 99. The ram head is heated by a 5 suitable electric heater arranged in said head.

The moistening roller carrying trough 89 is located in the path of movement of the ram and to permit of the strip applying 10 movement of the ram the trough is supported to have movement in line with the movement of the ram to have movement toward and away from the ram between the flanges of the strip supporting fingers and to have 15 lateral movement of the ram. The fingers 87 as stated are pivotally carried on the sides of the ram and are normally positioned with the finger flanges engaging in front of the face of the ram. To permit of the face of 20 the ram to impinge the strip against the overlapped edges of the sheet upon the mandrel the fingers are actuated to move them laterally. After the ram has receded from the mandrel the tube is ejected from the 25 mandrel and is delivered to one of a series of holders 105, shown as four in number, positioned in co-axial alinement with the mandrel as shown at T, by a pair of parallel ejector rods 106 slidably engaging in per- 30 forations in the standard 30 to have movement at diametrically opposite sides of the mandrel and spaced so that the ends of the rods will engage the ends of the tube on the mandrel, the mandrel being provided with 35 recesses 106' to permit of the engagement of the rods with the tube and the passage of the rods during the tube ejecting movement thereof. These rods are connected by a crosshead 107 whereby they are connected 40 to one end of a lever 108 supported to have movement on a vertical axis, the other arm of the lever being curved and carrying a roller 109 engaging a cam groove 110 in a cam fixed to the drive shaft.

45 The holders 105 are mounted upon a rotatable support to move in a horizontal path, said support being intermittently rotated to move the holder successively from tube receiving position to means to form 50 and apply a closure to one end of the tube, to advance the holder from said latter means to means to upset the material of the closure and tube to secure the two together, and then moving the holder to position to release the then formed receptacle or container 55 from the holder. The holders comprise arms extending radially from a head 106^a (Figure 1) mounted on a support 107^a fixed to the base to rotate on a vertical axis and 60 having a curved face, in the present instance the under face. A pair of flaps 107^b of segmental shape in cross section are pivotally or hingedly connected at their longitudinal edges to opposite sides of the arms and each 65 flap having a toggle link connection 108^c with

a cam follower 109^c engaging a cam groove 110 in a member fixed upon the holder support. The flaps when in contracted or closed position form a tube of truncated cone shape with the portion of less diameter adjacent 70 the holder support 107^a. The holder carrying head 106^a is intermittently rotated in arcs of 90 degrees by means of a pawl 111 pivotally carried by an arm 112 co-operating with an index 113 connected to the holder carrying head, the pawl actuating arm 112 being connected to and operated by a cam or eccentric 114 on the drive shaft operatively connected to said pawl carrying arm by a rod 115 pivotally connected to one arm 75 116 of a rocker pivotally supported upon a post fixed to the base and another arm of said rocker pivotally connected to the pawl carrying arm, as shown in Figures 1, 2 and 4. The holders are successively positioned 80 in line with the mandrel 29 to receive a tube ejected through the mandrel, and from said tube receiving position are successively advanced to means for forming and inserting a flanged disk as a closure to one end of the 85 tube T carried by the holder with a portion projecting from the holder as shown in Figures 1, 2 and 4.

The closure forming means comprises a punch and die mechanism carried by a standard 117 fixed to the top of the base or bed B to stamp disks from a paper web D fed to said mechanism from a roll rotatably mounted upon said standard. Disks are stamped from the web by a tubular punch 118 reciprocably mounted in a bore in the standard 117 cooperating with a circular opening 119 in a die head 120 fixed to the standard in line with the punch 118. The punch is reciprocated by cam followers 121 co-operating with cams 122 on the driving shaft connected to trunnions 123 extending laterally from the punch and through slots in the wall of the punch carrier. The disk after it is punched from the web is peripherally flanged by a forming plunger 124 reciprocable in the punch 118 and forcing the blanked disk through a portion of reduced diameter 125 in the head 120, said plunger 124 also operating to insert the 110 flanged disk into the end of the tube T carried in the holder as shown in Figure 8. The plunger 124 is reciprocated by a cam follower 126 connected to the plunger co-operating with a cam 127 on the drive shaft. Predetermined portions of the web D are intermittently fed between the die head and punch by means of a pair of feed rollers 128, 129, the roller 129 being positively rotated by a pawl 130 co-operating with a ratchet 125 wheel 131 rotatable with said roll, the pawl being actuated by a cam or eccentric 132 on the drive shaft operatively connected to the pawl by a cam follower 133 (Figure 4).

After the disk has been inserted in the end 130

of the tube the tube holder is rotated to position the same in line with one of a series of upsetting heads 134 operative to roll over the edge portions of the disk flange and tube 5 to form a bead and secure the disk within the tube, as shown at 135 in Figure 9. The upsetting heads are fixed to shafts 136 whereby said heads are rotatably mounted in a support 137 rotatably mounted by means of 10 a sleeve 138 in a bearing 139 mounted upon the base B. A series of upsetting heads 134 are provided in the present instance four in number, and are intermittently moved in an orbit about the axis of the head support 137 15 by intermittently rotating said head to bring the head successively in line with the successive tube holders. The head support 137 is intermittently rotated by a pawl 140 (Figures 1, 2 and 4) pivotally carried by a pivoted lever 141 co-operating with a ratchet wheel 142 (Figure 12) fixed to or integral with the sleeve 138, the pawl carrying lever 141 being actuated by a cam 143 on the drive shaft through a cam follower 144 operatively 20 connected to the lever. The upsetting head carrier is releasably locked in its advanced position by a pivoted pawl 145 co-operating with equidistantly spaced notches in an index head 146 fixed to or integral with the 25 sleeve 138. The pawl 145 is thrown into locking and unlocking position with the notches in the head by a cam 147 on the drive shaft through a cam follower 148 operatively connected to the pawl. The sleeve is 30 connected to the support 137, as shown at 149 to rotate therewith and to permit of axial movement of the support relative to the sleeve to move the heads toward and away from the tube holders. Axial movement is 35 imparted to the upsetting head support by a lever 150 pivotally supported on a vertical axis, one end of said lever having a bifurcation 151 arranged with pins 152 to engage an annular groove in a collar 153 fixed to the 40 index head carrier support. The other end of the lever 150 is arranged with means to co-operate with a cam 154 fixed on the drive shaft. 45 The upsetting heads 134 are rotated independently of the support 137 through a pinion 155 fixed upon each of the head shafts 136 meshing with a gear 156 (Figure 12) fixed to a shaft 157 rotatably mounted in the head support 137 and an arm 158 of the bearing for said support, and is driven from a suitable source of power as an electric motor E mounted upon the bed B operatively connected to the shaft 157 through a pinion 159 fixed to the motor shaft meshing with 50 a gear 160 fixed to the shaft 157. The upsetting heads 134 are rotated at high velocity and due to the frictional contact thereof with the material of the closure and tube in upsetting said material in securing the two together they become heated to a high de-

gree, and to permit of cooling after the closure has been secured to the tube the heads are successively brought into action as the successive tubes with closures are successively brought to position to be acted upon 70 by the heads. After the closure has been secured in a tube by the upsetting head a closure or container is produced as shown in Figure 7.

A curved guide member 161 (Figure 1) is 75 provided to co-operate with a tube in a holder in the movement of the latter from its tube receiving position to the closure applying means, and from the latter to the upsetting means to prevent accidental displacement of the tube from the holder during the movement of the latter to its successive positions. After the closure is secured in the tube by the upsetting means the holder support is moved to position the holder with 80 said tube diametrically opposite on the support to the closure forming means. As the closure approaches this position due to the engagement of the cam follower 109^a in the cam groove 110^a and the toggle link connection 108^a of said follower with the segmental sections or flaps of the holder said segments are expanded or moved outward 85 from the position shown in Figure 4 to that shown in Figures 1 and 2 releasing the tube 90 with the closure, or the receptacle, from the holder.

The containers as they are released from the holders are delivered to a conveyor 170 and delivered from said conveyor to a second 100 conveyor 171 to be transported to a paraffining plant the latter conveyor being actuated by a cam on the drive shaft S as shown in dotted lines in Figure 4, but as this does not form a part of the present invention detail illustration and description is not deemed necessary.

The fingers 87 to guide and retain the gummed strip adjacent the face on the ram, as stated are pivotally carried by the ram, 110 as shown in Figure 17, and to move said fingers away from the face of the ram as the strip is applied to the overlapped edges of the sheet upon the mandrel arms 175 having a pin and slot connection 176 with the ram support are pivotally connected to the fingers 87. As the ram is moved to strip applying position the arms 175 are moved therewith due to the pin and slot connection thereof with the ram support until the movement of said arms is arrested by the engagement of the ends of the slots with the pins when the ends connected to the fingers are moved outward and therewith the fingers 87 away from the arms. The moistening roller carrying trough 89 during the feeding and moistening of the gummed strip to the arm is positioned directly in the path of movement of the ram, and to permit of reciprocating movement of the ram 125 130

said trough is adjustably mounted to be moved toward and away from the ram. For this purpose the trough is carried by a slide 177 mounted in a bracket 178 pivotally supported upon the standard 30 (Figure 5), said arm being actuated by a pivoted bell crank lever 179 to one arm of which lever the slide is pivotally connected and the other arm of the lever carrying a cam follower to 10 co-operate with a cam on the shaft S.

Having thus described my invention I claim:

1. In apparatus of the class specified, a mandrel; means to wrap a sheet of material 15 around the mandrel with the longitudinal edges in overlapped relation; and means to moisten and apply a gummed strip to the overlapped edges of the sheet on the mandrel for the purpose specified.

2. In apparatus of the class specified, a mandrel; means to wrap a sheet of material 20 around the mandrel with the longitudinal edges in overlapped relation; means to feed a gummed strip a predetermined distance 25 adjacent to the overlapped edges of the sheet upon the mandrel and moisten said strip during the feeding thereof; and means to apply the moistened strip to the overlapped edges of the sheet upon the mandrel.

3. In apparatus of the class specified, a mandrel; means to wrap a sheet of material 30 around the mandrel with the longitudinal edges in overlapped relation; a support for a rolled gummed web; means to feed a portion 35 of said web adjacent to the overlapped edges of the sheet upon the mandrel; means to moisten the gummed surface of the web during the feeding thereof; and means to sever the fed and moistened portion of the 40 web and forcibly apply the same to the overlapped edges of the sheet upon the mandrel.

4. In apparatus of the class specified, a mandrel; means to wrap a sheet of material 45 around the mandrel with the longitudinal edges in overlapped relation; a support for a rolled gummed web; a reciprocable ram arranged to have movement toward and away from the overlapped edges of the sheet upon 50 the mandrel; means to feed and moisten a predetermined portion of the gummed web; means to retain the fed portion of the web adjacent to the face of the ram; and means to release said web retaining means from the 55 ram as the ram is moved to apply the strip to the overlapped edges of the material upon the mandrel.

5. In apparatus of the class specified, a mandrel; means to wrap a sheet of material 60 around the mandrel with the longitudinal edges in overlapped relation; a ram reciprocable toward and away from the mandrel; means to releasably support a gummed strip contiguous to the ram; a rolled gummed strip 65 web; means to feed a predetermined strip

of the web to the strip support of the ram and moisten said strip during the feeding thereof; means to sever the fed portion of the web; and means to move the strip supporting means to release the strip as the 70 ram is moved toward the mandrel to apply the strip to the overlapped edges of the sheet upon the mandrel.

6. In apparatus of the class specified, a mandrel; means to wrap a sheet of material 75 around the mandrel with the longitudinal edges in overlapped relation; a ram reciprocable toward and away from the mandrel; a support for a rolled web having a gummed surface; means to feed and moisten a predetermined portion of the gummed web and sever the fed portion from the web; and means to position the fed web to be applied to the overlapped edges of the sheet upon the mandrel as the ram is moved toward the 85 mandrel for the purpose specified.

7. In apparatus of the class specified, a mandrel; means to wrap a sheet of material 90 around the mandrel with the longitudinal edges in overlapped relation; a support for a rolled web having a gummed surface; and means to feed, moisten and sever a predetermined strip of said web and position the same relative to the overlapped edges of the sheet upon the mandrel.

8. In apparatus of the class specified, a mandrel; means to wrap a sheet of material 95 around the mandrel with the longitudinal edges in overlapped relation; and means to apply a moistened and severed web strip to 100 the overlapped edges of the sheet upon the mandrel under heat and pressure.

9. In apparatus of the class specified, a mandrel; a table for a pile of sheets; means 105 to feed a sheet from the pile to the mandrel; means to wrap said sheet about the mandrel with the edges in overlapped relation; and means to apply a moistened gummed strip to the overlapped edges of the sheet upon the mandrel.

10. In apparatus of the class specified, a mandrel; a table for a pile of sheets; a sheet support below the mandrel; means to feed a sheet from the table to the sheet support; means to wrap the sheet upon the sheet support around the mandrel with the longitudinal edges in overlapped relation; means to moisten and feed a gummed strip adjacent to the overlapped edges of the sheet upon the mandrel; and means to apply the moistened strip under pressure to the overlapped edges of the sheet upon the mandrel.

11. In apparatus of the class specified, a mandrel; a table for a pile of sheets; a sheet support below the mandrel; means to separate and feed a sheet from the pile and position it upon the sheet support; means to clamp the sheet in fixed relation to the mandrel; means to wrap the sheet around the mandrel while clamped thereto with 120

the edges in overlapped relation; a support for a rolled gummed web; means to feed, moisten and position a strip of the web relative to the overlapped edges of the sheet upon the mandrel; and means to apply said moistened strip to the overlapped edges of the sheet upon the mandrel under heat and pressure.

12. In apparatus of the class specified, a mandrel; an adjustable table for a pile of sheets; means to separate and deliver a sheet from the table to the mandrel; means to automatically elevate the table as the sheet is fed therefrom; means to wrap said delivered sheet around the mandrel and hold it upon the mandrel with the longitudinal edges in overlapped relation; and means to apply a moistened gummed strip to the overlapped edges of the sheet upon the mandrel under pressure.

13. In apparatus of the class specified, a mandrel; a table for a pile of sheets; a support for a sheet below the mandrel; means to separate and deliver a sheet from the pile and position said sheet upon the sheet support; means to lift the sheet from the support and clamp it to the mandrel substantially midway between its ends; fingers to engage and wrap the sheet around the mandrel and firmly hold it in position thereon with the longitudinal edges in overlapped relation; means to feed a moistened strip and position the same in juxtaposed relation to the overlapped edges of the sheet upon the mandrel; and means to apply said strip under pressure to the overlapped edges of the sheet upon the mandrel.

14. In apparatus of the class specified, a mandrel; a table for a pile of sheets; a support for a sheet below the mandrel; means to separate and deliver a sheet from the pile and position said sheet upon the sheet support; means to wrap the sheet upon the support around the mandrel with the longitudinal edges in overlapped relation; a support for a rolled gummed web; means to moisten and feed a predetermined strip of the web and position the same relative to the overlapped edges of the sheet upon the mandrel; means to sever said web strip; means to apply said severed strip under pressure to the overlapped edges of the sheet upon the mandrel; means to release the sheet wrapping means from the mandrel; and means to eject the formed sheet from the mandrel.

15. In apparatus of the class specified, a mandrel; a sheet support adjacent to said mandrel; means to clamp a sheet on said support substantially midway between its longitudinal edges against the mandrel; and means to wrap the free ends of the sheet under tension around the mandrel with the longitudinal edges in overlapped relation, comprising a plunger extending longitudi-

nally of and movable toward and away from the mandrel, two series of fingers pivotally supported on the plunger on parallel axes and parallel with the axis of the mandrel and yieldingly urged in a direction toward each other; and stops to limit the movement of the fingers in a direction toward each other; said fingers as the finger carrying plunger is moved toward the mandrel being adapted to wrap the free ends of the sheet around the mandrel.

16. In apparatus of the class specified, a mandrel; a sheet support adjacent to said mandrel; a plunger reciprocable toward and away from the mandrel to engage the sheet upon the support midway between its longitudinal edges and clamp the same to the mandrel; a second plunger movable toward and away from the mandrel; two series of opposed and oppositely curved fingers pivotally carried by said latter plunger on parallel axes parallel with the axis of the mandrel; means to yieldingly urge the fingers in a direction toward each other; stops to limit the movement of said fingers toward each other, said fingers being adapted to engage the sheet at opposite sides of the sheet clamping plunger as the finger carrying plunger is moved toward the mandrel and wrap said portions of the sheet around the mandrel under tension with the longitudinal edges in overlapped relation.

17. In apparatus of the class specified, a mandrel; means to wrap a sheet of material around the mandrel with the longitudinal edges in overlapped relation; means for moistening and feeding a gummed strip and applying the moistened strip to the overlapped edges of the sheet upon the mandrel to form a tube, means to eject the rolled sheet from the mandrel; means to receive and releasably support a tube ejected from the mandrel; and means to apply a closure to one end of the tube while carried by said holder.

18. In apparatus of the class specified, a tubular holder for releasably supporting a tube comprising longitudinally pivotally supported sections; a support for a rolled web; means for stamping a disk from the web; means for peripherally flanging said disk and inserting it in an end of the tube; means for rolling the edges of the juxtaposed disk flange and tube laterally to secure the disk within the end of the tube, and means for expanding the sections of the holder to release the tube therefrom after the disk has been secured therein.

19. In apparatus of the class specified, the combination of a mandrel; means to wrap a sheet around the mandrel with the longitudinal edges in overlapped relation; means to secure the overlapped edges of the sheet together on the mandrel to form a tube, means to eject a tube from the man-

drel; a tubular holder positioned to receive the tube ejected from the mandrel comprising longitudinally pivotally supported sections to releasably support a tube.

5. 20. In apparatus of the class specified, the combination of a mandrel; means to wrap a sheet around the mandrel with the longitudinal edges in overlapped relation; means to secure the overlapped edges of the 10 sheet together on the mandrel to form a tube; means to eject a tube from the mandrel; an adjustably supported holder adapted to be positioned to receive a tube ejected from the mandrel, comprising longitudinally pivotally supported sections to releasably support a tube; a support for a rolled web; means to stamp a disk from said web and peripherally flange said disk; means to position the tube holder for the insertion 15 of the flanged disk in one end thereof as said disk is flanged.

21. In apparatus of the class specified, the combination of a mandrel; means to wrap a sheet around the mandrel with the 25 longitudinal edges in overlapped relation; means to secure the overlapped edges of the sheet together on the mandrel to form a tube; means to eject the tube from the mandrel; an adjustably supported holder 30 adapted to be positioned to receive a tube ejected from the mandrel; comprising longitudinally pivotally supported sections to releasably support a tube; a support for a rolled web; means to stamp a disk from 35 said web and pivotally flange said disk; means to position the tube holder for the insertion of the flanged disk in one end thereof as said disk is flanged; means to roll the edges of the disk flange and tube 40 together to secure the disk in the tube; means to adjust the holder to position the same relative to said disk securing means; and means to expand the sections of the 45 holder after the disk has been secured in the tube to release the tube from the holder.

22. In apparatus of the class specified, the combination with means to form a sheet into a tube, of a rotatable adjustable support for a series of radially extending tube 50 holders, each holder comprising longitudinally pivotally supported sections to releasably hold a tube, said support being normally adjusted to position a holder to receive a tube from the tube forming means; means for forming and applying a closure 55 to one end of said tube; and means to intermittently adjust the holder support to successively present the holder to position to receive a tube from the tube forming means; the closure forming means and closure applying means.

23. In apparatus of the class specified, the combination with means to form a sheet into a tube; of a rotatably adjustable support for

a series of radially extending tube holders, 65 each holder comprising longitudinally pivotally supported sections to releasably hold a tube, said support being normally adjusted to position the holder to receive a tube from the tube forming means; means for forming and applying a closure to the tube; means for securing the closure in the tube; means to intermittently adjust the holder support to successively present the holder to the tube forming means, the closure forming 70 and applying means and the closure securing means; and means operative to expand the holder sections to release a tube therefrom when the latter is positioned intermediate the tube receiving a closure securing position thereof.

24. In apparatus of the class specified, the combination with means to form a tube, of a rotatably adjustable support having a series of radially extending tube holders, each 75 holder comprising longitudinally pivotally supported sections to releasably hold a tube; a support for a rolled web; means to stamp a disk and peripherally flange said disk and insert the flanged disk into a tube in a 80 holder; means to roll the edges of the disk flange and tube to secure the disk in the tube; means to expand the section of the holder to release the tube with the disk secured therein from the holder; and means to intermittently rotate the holder support to present the successive holders in sequence to the tube forming means, the disk forming and flanging means, the disk securing means 85 and the tube releasing means.

25. In apparatus of the class specified, the combination with means to form a sheet into a tube, of means to apply a closure to said tube including means to releasably hold the tube during the applying of the closure 90 thereto and to which the tube is delivered from the tube forming means, comprising a series of longitudinally pivotally supported segments, means rotatable on a vertical axis to support the holder in horizontal position; means to intermittently rotate said support to successively present the holder to position to receive a tube from the tube forming means, to closure applying and securing means, and to position to release the tube from the holder; a cam on the holder supporting means; and a cam follower to co-operate with said cam operatively connected to the holder segments and operable to expand the holder segments when the 95 holder is in tube releasing position.

26. In apparatus of the class specified, the combination with means to form a sheet into tubular form, of means to apply closures to the tubes formed by the tube forming means including a holder for the tube, a rotatable support for said holder, means to deliver a tube from the tube forming means to said 100

- holder, means to stamp a disk from a web and peripherally flange said disk and apply said flanged disk to the tube, means to intermittently advance the holder support to intermittently advance the holder support to 65
 5 present the tube to said disk stamping and flanging means, and means to roll over the edges of the disk flange and tube to secure the closure disk in the tube comprising a series of individually rotatable upsetting heads supported to have movement through 70
 10 the orbit about the common axis.
27. In apparatus of the class specified, the combination with means to form a sheet of material into a tube, of means to apply closures to said tubes including a holder to receive a tube from the tube forming means, a support for said holder rotatable on an axis transverse to the axis of the holder, disk forming and flanging means arranged 75
 15 to apply the flanged disk to the tube in the holder, means to upset the flanged portion of the disk and tube to secure the two together, and means to intermittently rotate the holder support to successively move the 80
 20 same from the tube receiving position to the disk forming and applying means, to the disk securing means, to tube releasing position and returned to position to receive another tube.
- 30 28. In apparatus of the class specified, the combination with means to form a sheet of material into a tube, of means to apply closures to said tubes including a holder to receive a tube from the tube forming means, 85
 35 a support for said holder rotatable on an axis transverse to the axis of the holder, disk forming and flanging means arranged to apply the flanged disk to the tube in the holder, means to upset the flanged portion 90
 40 of the disk and tube to secure the two together, comprising a series of upsetting heads, a support for rotatably supporting said heads and adapted to move said heads 95
 45 through an orbit about the axis of the support and impart axial movement to the heads, and means to rotate the heads independently of the support.
29. In apparatus of the class specified, the combination with means to form a sheet of material into a tube, of means to apply closures to said tubes including a holder to receive a tube from the tube forming means, a support for said holder rotatable on an axis transverse to the axis of the holder, disk 100
 50 forming and flanging means arranged to apply the flanged disk to the tube in the holder, means to upset the flanged portion of the disk and tube to secure the two together, comprising a series of upsetting heads, a support for the heads mounted to have rotative and axial movement, means to 105
 55 rotatably mount the heads upon the support disposed around the axis of said support, a pinion connected to each of said heads, a rotatable shaft journaled in the head support, a gear on said shaft meshing with the head pinion, and means to rotate said shaft independent of the support.
30. In apparatus of the class specified, a mandrel, and means to wrap a sheet of material around the mandrel comprising a member reciprocable in a direction toward and away from the mandrel, a pair of shafts rotatably carried by said member to extend parallel with the mandrel, fingers fixed 110
 60 to said shafts in opposed and staggered relation, means to yieldingly urge said fingers in a direction toward each other and into engagement with stops, said fingers being adapted to yieldingly engage and wrap the sheet around the mandrel against the action of said yielding means by the movement of the reciprocable member.
31. In apparatus of the class specified, the combination with means to form a sheet into a tube, a tubular holder to receive a tube delivered from the tube forming means, said holder comprising pivotally supported segments adapted to be moved to position to receive and hold a tube therein and to be 115
 65 expanded to release a tube from the holder, a support upon which the holder is rotatably mounted, means to stamp a disk from a web and peripherally flange the same, means to intermittently position the holder to receive 90
 70 the flanged disk in the end thereof and to present the tube with the disk to upset means, a cam groove in the holder support, a cam follower to engage said cam groove and operatively connected to the holder segments, said cam being constructed and arranged to actuate the holder sections through the cam follower to expand said sections and release a tube from the holder when the holder is positioned midway between the 100
 75 disk upsetting means and the tube receiving means.
32. In apparatus of the class specified, a mandrel; a sheet support adjacent to the mandrel; a plunger operable to clamp the sheet upon the support against the mandrel substantially midway between its ends, and means to wrap the free ends of the sheet around the mandrel under tension and hold the same upon the mandrel with the longitudinal edges in overlapped relation.
33. In apparatus of the class specified, a mandrel; a sheet support adjacent to the mandrel; a plunger operable to clamp the sheet upon the support against the mandrel substantially midway between its ends; a series of fingers pivotally supported on parallel axes parallel with the axis of the mandrel and yieldingly urged in a direction toward each other; and means to move the finger support in a direction toward the mandrel to cause the fingers to engage the portions of the sheet at opposite sides of the sheet 120

clamp to wrap the sheet under tension around the mandrel with the longitudinal edges in overlapped relation.

34. In apparatus of the class specified, a mandrel, means to wrap a sheet about the mandrel with the longitudinal edges in overlapped relation, means to feed and adhesively apply a sealing strip to the overlapped edges of the sheet upon the mandrel to form

a tube, means to eject the rolled sheet from the mandrel, a holder to receive the tube as it is ejected from the mandrel, and means to apply a closure to one end of the tube while carried by said holder.

Signed at New York city, in the county of New York and State of New York this 14th day of April, 1921.

IRVING STANLEY.
